UNITED STATES PATENT OFFICE.

JOSEPH W. BARNA, OF CHICAGO, ILLINOIS.

DESIGN FOR A SHOE.

No. 39,893.

Specification for Design.

Patented March 23, 1909.

Application filed June 8, 1908. Serial No. 437,457. Term of patent 14 years.

To all whom it may concern:

Be it known that I, JOSEPH W. BARNA, a citizen of the United States, residing at Chicago, in the county of Cook and State of Illinois, have invented a new, original, and ornamental Design for Shoes, of which the following is a specification, reference being had therein to the accompanying drawing, forming part thereof.

In the drawing Figure 1 is a rear elevation of a shoe, and Fig. 2 is a fragmentary view showing the rear portion of the shoe in side elevation, showing my new design.

The reference letter *a* indicates the shoe, and the letter *b* the metallic loop attached to the rear portion thereof.

I claim:

The ornamental design for a shoe, as shown.

JOSEPH W. BARNA.
